UNITED STATES PATENT OFFICE.

LEWIS SHIREMAN, OF MUNCIE, INDIANA.

DESIGN FOR A SAW-HANDLE.

47,547.

Specification for Design.

Patented July 6, 1915.

Application filed November 11, 1914. Serial No. 871,619. Term of patent 14 years.

To all whom it may concern:

Be it known that I, LEWIS SHIREMAN, a citizen of the United States, residing at Muncie, in the county of Delaware and State of Indiana, have invented a new, original, and ornamental Design for Saw-Handles, of which the following is a specification, reference being had to the accompanying drawing, forming a part thereof.

Figure 1 is a perspective view of a saw

handle, showing my new design; Fig. 2 is an end view; and Fig. 3 is a plan view.

I claim:

The ornamental design for a saw handle, as shown.

LEWIS SHIREMAN.

Witnesses:

L. R. WOOD,
E. R. SHIREMAN.
